Primary Examiner — Paula Allen Greene*(74) Attorney, Agent, or Firm* — Yong-Ting Chen; Law Office of Michael Chen(57) **CLAIM**

The ornamental design for a gaming headphone, as shown and described.

DESCRIPTION

FIG. 1 is a perspective view of the gaming headphone showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of portion 9 in FIG. 1; and,

FIG. 10 is a partial enlarged view of portion 10 in FIG. 2. The dot dash broken lines encircling portions of the gaming headphone in FIGS. 1 and 2 and illustrated in the enlarged views of FIGS. 9 and 10 form no part of the claimed design.

1 Claim, 10 Drawing Sheets(56)
